UNITED STATES PATENT OFFICE.

CHARLES W. HOWELL, JR., OF NEWARK, NEW JERSEY, ASSIGNOR TO THE WAGNER TYPEWRITER COMPANY, OF NEW YORK, N. Y.

RULING AND ORNAMENTING MECHANISM FOR TYPE-WRITING MACHINES.

SPECIFICATION forming part of Letters Patent No. 674,416, dated May 21, 1901.

Application filed December 28, 1900. Serial No. 41,323. (No model.)

To all whom it may concern:

Be it known that I, CHARLES W. HOWELL, Jr., a citizen of the United States, residing at Newark, Essex county, State of New Jersey, have invented certain new and useful Improvements in Ruling and Ornamenting Mechanism for Type-Writing Machines, of which the following is a specification.

My invention relates to type-writing machines, and more particularly to mechanism for ruling and ornamenting; and the object of said invention is to provide simple and efficient mechanism with the aid of which ruling and ornamental work can be readily and effectively accomplished.

To this end my invention consists in the novel arrangement and combination of parts hereinafter described and claimed.

In the accompanying drawings, wherein like numerals indicate corresponding parts in the various views, Figure 1 is a central sectional view, taken from front to rear, of one form of type-writing machine embodying my invention. Fig. 2 is an enlarged fragmentary front elevation of the same. Fig. 3 is a detail plan view of the parts represented in Fig. 2. Fig. 4 is a fragmentary detail sectional view, with parts broken away, of a portion of the mechanism to be hereinafter described. Fig. 5 is an enlarged detail front view of the imprint-roller and the mechanism for carrying the same, with parts removed for the purpose of clearer illustration. Fig. 6 is a plan view of said mechanism. Fig. 7 is a detail side view of another form of imprint-roller. Fig. 8 is a transverse sectional view taken through the keys 51 and 28, the section being taken through the lug 59. Fig. 9 is a detail face view of the plate 20 and the parts coöperating therewith.

The mechanism constituting the present invention is shown applied to an "Underwood" type-writing machine, though it should be understood that the improvements may be applied to any type-writing machine wherein they may be found available.

In Fig. 1 of the drawings I have shown sufficient number of parts of an Underwood machine to illustrate my invention, and in this figure, 1 designates the framing of the machine, and 2 indicates the segment in which

the type-bars 3 are mounted, the pivot for such type-bars being indicated at 4. While I have illustrated only a single type-bar and its connections, it will be understood that each of the type-bars 3 is connected to a link 5, which is pivoted to the framing of the machine, as indicated at 6, and is likewise operatively connected to a key-lever 7, as indicated at 8 in dotted lines. The key-lever 7 is fulcrumed to the framing of the machine, as shown at 9, and is provided with the usual finger-key 10. A platen 11 is provided which moves upon a traverse-rod 12. A type-bar guide 13 is secured to the segment 2 and extends in front of the platen to guide the type-bar in its movement to the printing-point. Interposed between this type-bar guide and platen is a ribbon 14, which is moved into the path of the type during the printing stroke by a lever 15, which is connected to the carriage-escapement and is operated to carry the ribbon-guide and ribbon into and out of the path of the imprint during each stroke of the type-bar.

So much of the machine as I have thus far described constitutes a part of the Underwood type-writing machine.

Secured to the segment 2 or to any other fixed portion of the machine is a guide-plate 16, which in the present instance is provided with slots 17, (see Fig. 4,) through which project guiding pins or screws 18 19. The pins 18 and 19 are secured to a vertically-movable plate 20, which is maintained in the raised position by a spring 21. This spring 21 is secured at one end to a pin 22 and at its opposite end to the guide-pin 18. Connected to the plate 20 is a yoke 23, that is adapted to receive and constitute a bearing for the pivots 24 of the arm 25, which I will designate as an "imprint-roller-carrying arm." The plate 20 has an aperture 26, which is shown in dotted lines in Fig. 4 and in Fig. 9. This aperture is adapted to receive the cam-like projection 27 of the so-called "key" 28, which is pivoted to a fixed portion of the machine, as indicated at 29, and has a suitable finger-piece 30 at its outer end, by means of which it may be turned on its pivot. When this key 28 is moved from its normal position, it causes the cam-like projection 27 to be forced

into the recess 26 in the plate 20, thereby causing said plate to be forced against the tension of its spring 21 to move the plate 20, the yoke 23, and imprint-roller-carrying arm 5 25 in a vertical direction for purposes which will hereinafter more fully appear. This imprint-roller-carrying arm may be constructed of a single piece; but I prefer to construct it of a plurality of sections, as clearly indicated 10 in Figs. 5 and 6 of the drawings. In these figures it will be observed that the arm proper, 25, terminates at a hinged joint 31, at which point a link 32 is pivotally connected to the arm proper, 25. The rod 33, which constitutes 15 the pivot that unites the arm proper, 25, to the link 32, is provided with a finger-piece or button 34 and is rigidly secured to the link 32, as indicated, by the pins 35. The link 32 in turn is pivoted or hinged to a carrying-piece 36, as indicated at 37. This carrying-piece 36 is provided with a slotted portion 38, into the slot of which extends a pin 39, that projects from an arm 40, secured to the arm proper, 25. The carrying-piece 36 has loosely 20 pivoted thereto an imprint-roller 41, which may be readily removed by a withdrawal of the screw-pivot 42. This imprint-roller 41 is provided with a peripheral imprint-surface 43, which is of the same character throughout 25 its extent. In Fig. 5 it will be observed that this peripheral printing-surface is adapted to print a solid line, whereas the roller shown in Fig. 7 of the drawings is adapted to print a series of dots. It is obvious that any suitable 30 printing-surface, such as a series of stars and the like, may be provided upon the imprint-roller. When the operator desires to change the character of the imprint-roller, it is merely necessary to remove the pivotal screw 42 and substitute an imprint-roller having 35 the desired imprint-surface. Pivoted to the carrier 36, adjacent to the imprint-roller, is an inking-roller 44. The periphery of this inking-roller is adapted to contact with the 40 periphery of the imprint-roller in order to ink the imprint-surface thereof and to rotate the imprint-roller by frictional contact. Thus I prefer to form the inking-roller with a groove 45, that is adapted to receive the printing-50 surface of the imprint-roller and at the same time permits the other peripheral surfaces of the inking-roller to contact with the general periphery of the imprint-roller, as indicated in Figs. 2 and 6 of the drawings.

55 The pivot 33, which unites the arm 25 and the link 32, is provided with a locking device for maintaining the carrier 36 in the position to which it is moved by the hand-operated button 34. In the present instance these 60 locking means consist of a disk 46, that is provided with notches 47. A spring-pressed pawl 48 is pivoted to the arm 40, and the nose 49 of this pawl is adapted to be forced into either of the notches 47 in the disk to maintain 65 the carrier and the imprint-roller carried thereby in either of the positions represented in full and in dotted lines in Fig. 5 of

the drawings for purposes which will herein-after more clearly appear.

A bracket 50 is secured to the framing of 70 the machine, and it is on this bracket that the pivot 29 of the key 28 is supported. This pivot 29 likewise constitutes the pivot for a second key 51, which, like the key 28, is provided with a finger-piece 52 at its outer end. 75 The inner end of the key 51 is connected to a link 53, which in turn is connected to a bell-crank lever 54, that is pivoted to the bracket 50, as indicated at 55. The opposite end of 80 this bell-crank lever is connected to a short link 56, that in turn is united to an arm 57, that projects from the pivot 24 of the arm 25. It will thus be seen that the portion 58 constitutes in a sense a rock-shaft that is provided with two arms—one the arm 25 and 85 the other the arm 57. By moving the key 51 from the full-line to the dotted-line position indicated in Fig. 3 of the drawings the so-called "rock-shaft" 58 will be turned on its axis, and the imprint-roller 41 will be conveyed to the printing position above the type-bar guide 13, as indicated in dotted lines in 90 Fig. 3 of the drawings. When the key is released, the parts will be restored to their normal or full-line position by a spring 58^X, which 95 spring is connected at one end to a pin projecting from the bracket 50 and at the other end to the arm 25. When the imprint-roller is set in the manner indicated in full lines in 100 Fig. 5 and the key 51 is moved to the dotted-line position indicated in Fig. 3 of the drawings, the imprint-roller will be brought to such position that the imprint-surface thereof will rule a straight line on the paper by moving the carriage and platen along the machine. If it is desired to rule or to cause an 105 ornamental line to be imprinted in a direction parallel to the sides of the paper, it is merely necessary to turn the button 34, thereby causing the imprint-roller to be moved to 110 the dotted-line position indicated in Fig. 5 of the drawings, and a movement of the key 51 will cause the imprint-roller to be brought to the printing position. A rotation of the 115 platen around its axis at this time will cause an imprint to be made parallel to the sides of the paper.

From an examination of Figs. 2, 3, and 8 of the drawings it will be observed that the key 28 is provided with a right-angled projection 120 or lug 59. This lug 59 extends into the path of the key 51, so that a movement of the key 28 from the full-line to the dotted-line position in Fig. 3 will cause the key 51 to be moved with it. This movement of the key 28 brings 125 about a vertical downward movement of the plate 20 by reason of the cam 27 on said key contacting with the apertured portion 26 of said plate 20. This movement of the plate 20 will cause the arm 25 and the parts carried thereby to be lowered, so that the imprint-roller will assume a different position when 130 it is forced to the dotted-line position indicated in Fig. 3. This movement of the plate

20, which constitutes a support for the imprint-roller, is for the purpose of providing double-line ruling or double ornamental lines. Thus, for instance, for double underscoring 5 it is merely necessary to first move the key 51, when the imprint-roller will be conveyed to the printing position, and the carriage may be moved longitudinally to cause a line or imprint to be made. After this line is completed 10 the key 28 is moved to shift the printing position of the imprint-roller and to simultaneously convey the imprint-roller to the printing position by reason of the lug 59 on the key 28 contacting with the key 51, thereby 15 causing the key 51 to move with the key 28. Thus the shifting operation to vary the imprint position of the roller and the movement of the roller from the normal to the printing position is accomplished by a single movement 20 of the key 28.

Fixed upon an arm 60, which may constitute a portion of the yoke 23, is a segmental inking-pad 61. The arc of this segmental pad is drawn from the pivotal center of the 25 arm 25, so that the inking-roller 44 will contact with the pad 61 in the movement of the former with the imprint-roller to and from the printing position. This contact with the segmental pad causes the inking-pad to be 30 rotated during its movement toward the printing position, and the rotary motion thus imparted to the inking-pad is transmitted to the imprint-roller, so that its entire printing-surface will be inked during its movement to 35 and from the printing position, so that when it attains the printing position the entire printing-surface will be inked. It will be seen that the contact of the peripheral printing-surface of the imprint-roller upon the paper 40 will cause the same to be rotated to bring a newly-inked surface into contact with the paper as the paper progresses and that this rotary movement thus imparted to the imprint-roller will cause the inking-roller 44 to be 45 rotated, thus automatically and constantly inking the imprint-surface of the roller 41.

From the foregoing it will be observed that the inking-roller 44 partakes of the bodily movement of the imprint-roller to or from operating 50 or printing position and likewise imparts a rotary movement to the imprint-roller. In the act of printing the imprint-roller imparts a rotary movement to the inking-roller.

I prefer to have the imprint-roller operate 55 directly upon the paper and to automatically ink the imprint-surface of said roller, for the reason that a clearer line or imprint may be made and inks of different colors from those used on the machine may be employed. Nevertheless 60 it is obvious that the so-called "imprint-roller" may be arranged to contact with the ribbon 14 and that the lines or other characters imprinted upon the surface of the paper may be accomplished through the contact 65 of the imprint-roller with the ribbon.

It will be observed that by my invention I have provided a simple and efficient device

with the aid of which ruling or ornamental work can be accomplished and that lines or characters may be imprinted continuously 70 upon the surface of the paper either in a direction parallel to the top and bottom of the paper or to the sides thereof.

While I have shown and described with considerable detail one form of mechanism 75 embodying my invention, I would have it understood that various changes may be made in the construction without departing from the spirit of my invention.

Having described my invention, what I 80 claim, and desire to secure by Letters Patent, is—

1. In a type-writing machine, the combination of a platen, a loosely-mounted imprint-roller coöperating therewith, means for moving 85 said roller into and out of contact with the platen and means for automatically inking said roller throughout its periphery in the movement of the imprint-roller to or from the printing position. 90

2. In a type-writing machine, the combination of a platen, type-carriers which coöperate with said platen, keys for operating said carriers, a loosely-mounted imprint-roller coöperating with the platen, means for moving 95 said roller into and out of contact with said platen and means for shifting said roller laterally so as to vary the printing-line of said roller with relation to the line of characters adapted to be written by the type on the type-carrier. 100

3. In a type-writing machine, the combination of a platen, type-carriers which coöperate with said platen, means for operating said carriers, a loosely-mounted imprint-roller coöperating with the platen, a movable support 105 for said roller, means for moving said support so as to vary the point of imprint of the roller below the line of print produced by the type-carriers whereby a plurality of lines can be 110 produced by the imprint-roller below a written line, and means for moving said roller into and out of contact with said platen. 115

4. In a type-writing machine, the combination of a platen, type-carriers which coöperate with said platen, keys for operating said carriers, a loosely-mounted imprint-roller coöperating therewith, a movable support for 120 said roller, means for moving said support so as to vary the point of imprint of the roller, means for moving said roller into and out of contact with said platen and means for adjusting said roller so as to vary the direction of the line of imprint thereof with relation to the ordinary printing-line produced by the 125 type on the type-carriers. 130

5. In a type-writing machine, the combination of a platen, a loosely-mounted removable imprint-roller coöperating therewith and means for moving said roller into and out of contact with said platen, whereby the imprint-roller may be removed and another substituted therefor. 135

6. In a type-writing machine, the combina-

tion of a platen, a loosely-mounted imprint-
5 roller coöperating therewith, means for moving
said roller into and out of contact with
said platen and means for detaching said im-
print-roller from the moving means therefor,
whereby the imprint-roller may be removed
and one of a different character substituted
therefor.

7. In a type-writing machine, the combina-
10 tion of a platen, a ribbon, an imprint-roller
adapted to print by direct contact with the
paper, means for moving said imprint-roller
into and out of contact with the platen and
15 out of the path of the ribbon and means for
automatically rotating the imprint-roller in
its movement toward the platen in order to
automatically ink said roller.

8. In a type-writing machine, the combina-
20 tion of a movable platen, an imprint-roller
adapted to print by direct contact with the
paper carried by the movable platen, means
for moving said imprint-roller into and out of
25 contact with the platen and means for auto-
matically inking said imprint-roller, said inking
means comprising a fixed element and a
coöperating element which moves with the
imprint-roller.

9. In a type-writing machine, the combina-
30 tion of a platen, an imprint-roller adapted to
print by direct contact with the paper, means
for moving said imprint-roller into and out
of contact with the platen and means for auto-
35 matically inking said imprint-roller, said inking
means comprising a fixed element and
a coöperating element which moves with the
imprint-roller in its movement to and from
the printing position and which contacts with
40 the fixed element in its movement.

10. In a type-writing machine, the combi-
45 nation of a platen, a loosely-mounted imprint-
roller adapted to print by direct contact with
the paper on the platen, means for moving
said roller into and out of contact with the
50 platen, an inking-roller in contact with said
imprint-roller and adapted to be moved there-
with toward and away from the printing po-
sition and means for rotating the inking-roller
during the movement of the imprint-roller to
55 and from the operative position.

11. In a type-writing machine, the combi-
55 nation of a platen, a loosely-mounted imprint-
roller adapted to print by direct contact with
the paper on the platen, means for moving
said roller into and out of contact with the
60 platen, an inking-roller in contact with said
imprint-roller and adapted to be moved there-
with to and from the printing position, means
for rotating the inking-roller during the
movement of the imprint-roller to and from
65 the operative position said means for rotat-
ing the inking-roller comprising an inking-
pad with which said inking-roller contacts
during the movement of the printing-roller
to and from the printing position, whereby
the inking and imprint rollers are automati-
cally rotated in their movement to and from

the printing position and the peripheral print-
ing-surface of the imprint-roller is automati-
cally inked.

12. In a type-writing machine, the combi-
70 nation of a platen, loosely-mounted imprint
and inking rollers, a pivoted arm upon which
said rollers are carried and a segmental inking-
pad the arc of which is drawn around the
pivot of the arm which carries the said rollers. 75

13. In a type-writing machine, the combi-
75 nation of a platen, loosely-mounted imprint
and inking rollers, a pivoted arm upon which
said rollers are carried, a segmental inking-
pad the arc of which is drawn around the 80
pivot of the arm which carries the said rollers
and means for shifting said arm laterally to
change the printing position of the printing-
roller.

14. In a type-writing machine, the combi-
85 nation of a platen, type-carriers which coöp-
erate with said platen, keys for operating said
carriers, a loosely-mounted imprint-roller, an
arm upon which said roller is mounted, a mov-
90 able support for said arm and means for mov-
ing said support to vary the printing position
of said roller.

15. In a type-writing machine, the combi-
95 nation of a platen, a loosely-mounted imprint-
roller, an arm upon which said roller is mount-
ed, a key for moving said roller into and out
of contact with the platen, a movable sup-
port for said arm and a second key for mov-
ing said support to vary the printing position
of said roller. 100

16. In a type-writing machine, the combi-
105 nation of a platen, an imprint-roller, a key
for moving said imprint-roller into contact
with the platen and a separate key for simul-
taneously moving said imprint-roller into con-
tact with the platen and for changing the
printing position of said imprint-roller.

17. In a type-writing machine, the combi-
110 nation of a platen, an imprint-roller, a key
for moving said imprint-roller into contact
with the platen, a separate key for changing
the printing position of said imprint-roller,
said keys being so combined that the first-
115 mentioned key may be moved independently
of the second key and so that said second key
will, when moved, operate the first-mentioned
key.

18. In a type-writing machine, the combi-
120 nation of a platen, an imprint-roller, a key
for moving the said imprint-roller into con-
tact with the platen, a separate key for simul-
taneously moving said imprint-roller into
contact with the platen and for changing the
printing position of said imprint-roller and
means for automatically inking said imprint-
roller. 125

19. In a type-writing machine, the combi-
130 nation of a platen, an imprint-roller, a key
for moving said imprint-roller into contact
with the platen a separate key for changing
the printing position of said imprint-roller,
said keys being so combined that the first-

mentioned key may be moved independently of the second key and so that the second-mentioned key will, when moved, operate the first-mentioned key and means for automatically inking said imprint-roller.

20. In a type-writing machine, the combination of a platen, an imprint-roller the axis of which is at substantially a right angle to the length of the platen when in any one of several printing positions and means for shifting said roller in the general direction of its axis so as to vary the printing position thereof.

21. In a type-writing machine, the combination of a platen, an imprint-roller, means for moving said roller into and out of contact with the platen, means for changing the printing position of said roller, means for changing the position of the imprint-roller so as to change the position of the axis thereof and means for automatically inking said imprint-

roller in its movement to and from the printing position.

22. In a type-writing machine, the combination of a platen, an imprint-roller, means for moving said roller into either of two positions, the axis of said roller when in either position being at right angles to the position of the axis of said roller when it is in the other position, the printing contact in both positions being in the same horizontal plane, means for securing the roller against bodily movement in either of said positions, means for moving the imprint-roller into and out of contact with the platen and means for automatically inking the imprint-roller in its movement toward the printing position. 35
